UNITED STATES PATENT OFFICE

GEORGE WM. KEILHOLZ, OF DETROIT, MICHIGAN

TOY ROLLER COASTER

Application filed April 22, 1929. Serial No. 356,926.

This invention relates to mechanical toys, and more particularly to a toy roller coaster of the type, that is mechanically and automatically operated.

Most toys of this character, with which I am familiar, are continuously operated, and consequently, the operating period is extremely limited, thus necessitating the frequent winding of the spring operated motor.

It is the object of my invention to materially increase the operating efficiency of toys of this character by providing an automatic control for the operating mechanism, that will allow the toy to run for longer periods of time, and which will decrease the frequency in which the operating motor of the spring type must be wound.

A further object of my invention is to increase the popularity of toys of this character by providing an automatic control for the operating motor, that automatically turns the same "off" and "on" at predetermined times, thus providing a novel and interesting toy, which will attract the interest of the child.

A still further object of my invention is to provide a novel toy of this character, that comprises a plurality of operating motors, and a novel controlling means therefor, which automatically turns the same "off" and "on" at predetermined times, but which causes the rolling equipment associated therewith to be in motion at all times, and to be controlled in a manner similar to the movement of the roller coasters in amusement parks, which are of common knowledge.

For a more detailed understanding of my invention, reference may be had to the accompanying drawings, which illustrate one form which my invention may assume, and in which:

Fig. 1 is a plan view of my toy roller coaster.

Fig. 2 is a side view thereof.

Fig. 3 is a transverse sectional view of a part of the structure, showing the track and how the same can be supported from the superstructure.

Fig. 4 is a detailed view of the means for

elevating the cars from a lower to a higher level.

Fig. 5 is a detailed view, partly in section, and illustrating the motor for said elevating means, and the control therefor. 55

Fig. 6 is a plan view of another motor that is associated with the roller coaster, and showing the control therefor and the means for bringing the cars to rest at a predetermined place. 30

Fig. 7 is a detailed view showing the trip for setting the motor, illustrated in Fig. 6, into operation.

Fig. 8 is a side elevational view of a modified form of construction, in which electric motors are utilized for supplying the motive power to operate the several mechanisms. 65

As illustrated in the accompanying drawings, my toy roller coaster is preferably constructed as a unit. It comprises a superstructure, designated as a whole by the reference character "A", and consists of the base 10, uprights or posts 11, and the horizontal bracing members 12. These posts and associated struts, comprising the superstructure, may 70 preferably consist of angle bars, channels and rods, which may be secured together in any suitable manner. If preferred, this superstructure can be secured together by bolts or other suitable fastening devices, 75 which makes it possible to retail the toy in a knock-down condition, but which can be readily and easily set up by the purchaser. Thus, it is possible to pack the toy into boxes of minimum size to conserve shipping and 80 storage space. 85

A continuous track is arranged to be supported by this superstructure, and if desired, various track designs may be supported thereby, with various curves and dips. The 90 track consists of a pair of angle bars 13, constructed of relative light metal or other suitable material, that may be bolted as at 14, or otherwise secured to the horizontal supports, such as the channel sections 15, 95 which I preferably include as a part of my superstructure. These channel sections are preferably located in an inverted position, and bolted or otherwise secured to the posts 11, or to the horizontal bracing members 12, 100

as at 16. I also find that this superstructure may be built up of wooden struts and posts, bolted or otherwise secured together in any suitable manner.

The track is designed to be continuous, and may be best described by beginning at that portion, which is located at the lowest elevation, designated by the reference character "B". The track is then inclined sharply upwardly, as at "C", to the highest level "D". From then on the track is laid out in a plurality of dips, designated in general by "E", gradually lowering in elevation until it reaches the terminal point "F", where the track is preferably laid perfectly level for a short distance, but at a slightly higher level than "B". The track is then continued in a gradual incline downward to "B", said incline being sufficient to cause the cars to roll by gravity to the lowest level. The track located between "D" and "F" is so designed, that the cars will roll by gravity, attaining sufficient momentum in rolling down into the dips "E" to carry the cars up the next incline, and thence roll into the next dip. The construction of the track is obviously similar in general design to the roller coasters, as built in amusement parks and the like.

The motive power for elevating the cars from "B" to "D" up the sharp incline "C", consists of a spring motor 20 of any suitable standard design, which is operatively connected to a driving shaft 21. This shaft 21 has a sprocket wheel 22 secured thereto, which in turn, drives a sprocket chain 23, the other end of the loop formed by the sprocket chain, passing around a sprocket wheel 24, that is supported adjacent to the high level point "D". Preferably, the sprocket chain 23 is caused to be supported along the incline "C" in any suitable manner, so that the same will not sag. This chain has a plurality of lugs 25 attached thereto, which are arranged to engage the axle or a lug 40 carried by the undercarriage of the cars, to move the cars up the incline. Preferably, the chain or cable is designed to carry the cars over the crown at the top of the incline, to insure the cars of being positively propelled into the next zone. Care must be exercised in the design of this portion of the mechanism, so that two or more cars may be coupled together, and the entire train carried over the crown at the top of the incline, and the entire train started on its way into the next zone, where the same will roll by gravity over the several dips and hollows, until the train is brought to rest at the terminal point "F".

The operating motor is arranged to be started only when a car or a train arrives at the base of the sharp incline, and is stopped when the car or train is carried over the crown at the top of the sharp incline. A trip 26 is located in advance of the lowest level

"B", and consists of an arm 27, pivoted at 28 to a bracket or other suitable support, one end of said arm carrying the trip 26, and the other end being provided with a downturned catch or hook 29, that is arranged to engage in a recess 30 carried by the spring driven wheel 31 of the spring motor. The arm is preferably extended and provided with a downturned end portion 32, that is arranged to stop the fan governor 33. As the car or train rolls along the incline from "F" to "B", it strikes and depresses the trip 26, causing the downturned portions of the arm to be retracted for releasing the spring motor, thereby setting the same into operation. The spring driven wheel is rotated at a relatively slow speed, and is stopped upon the completion of one complete revolution, the hook 29 being yieldingly forced by a spring 34 into the recess, to effect the stopping, and at the same time, the governor is also stopped by members 32. The operating period of the motor 20 is so designed, as to be sufficient to carry the car or train over the crown at the top of the sharp incline "C".

The car is thus propelled into the next zone, in which the several dips "E" are located, and rolls by gravity to the terminal point "F". (See Fig. 6.) Braking means are located at this point to bring the cars to rest on a level portion of the track. This braking means may consist of any suitable mechanism or friction means, but I preferably provide the resilient members 41, which may be punched out of the track to yieldingly engage the car. A second car, or train is arranged to be carried around the track, the successful operation of the mechanism being dependent upon the use of at least two cars or trains. This second car is carried up the sharp incline "C", as described above, and when the same reaches the top, it strikes and depresses the trip 35 carried by the arm 36, and releases a spring motor 37 in a manner that is similar to operation of the mechanism for releasing the spring motor 20. The motor 37 operates the chain or cable 38, which carries the lugs 39, that are adapted to engage the undercarriage of the first mentioned car or train, which has come to rest at the terminal point "F". The car or train is thus propelled onto the incline located between "F" and "B", the car or train being caused to slowly roll down the incline to point "B", where it is picked up by the chain or cable 23, and once again started on a trip around the track. The design is such, that the second car or train has reached the point "F", and has come to rest, before the first car or train again reaches the top of the sharp incline "C", where it actuates the trip 35. Thus, it will be seen, that the cars or trains are in continuous motion, the said cars or trains being only momentarily stopped, and then propelled on their way

again. Some of the cars or trains are always in motion.

From the foregoing description, it will be further noted, that I have provided a toy, which is automatic in its operation, the cars or trains being propelled around the track, and being momentarily and automatically stopped at the terminal point "F". The spring motors are intermittently and automatically operated, and thus, it is quite obvious, that the mechanism will run for quite a long period of time without rewinding. The novel operation of the toy, which is very realistic, will attract the interest of the child, and is very entertaining as well as instructive.

In Fig. 8, a modified construction is illustrated, and which employs substantially the same track construction. In place of the spring motor 20, an electric motor 51 is employed for operating the elevating chain or cable 23. The motor 51 is started, when a car or train depresses the trip 52, thus closing a switch 53, and thereby permitting the electric current to flow to the motor.

Similarly, the electric motor 60 can be substituted for the spring motor 37, and may be started by actuating the trip 61, thus closing the switch 62 in the electric circuit.

Both electric motors are arranged to be automatically stopped at a predetermined time. A trip 70 is suitably connected to the switch 53 so that when the trip is depressed, the switch will be opened to break the circuit to the motor 51. Similarly, a trip 71 is operatively connected to the switch 62 and may be actuated to open the said switch 62 to break the electrical circuit to the motor 60.

Although I have illustrated but one form of my invention and have described in detail but a single application thereof, it will be apparent to those skilled in the art to which my invention pertains, that various modifications and changes may be made therein without departing from the spirit of my invention or from the scope of the appended claims.

I claim:

1. A toy roller coaster, having in combination, a continuous track on which a plurality of rolling bodies are supported, said track having a portion thereof positioned at a higher level than the remaining portions of the track to permit the rolling bodies to move by gravitational force from the higher to the lower level of said track, elevating means for carrying the rolling bodies from the lower to the higher level, means for controlling the operation of said elevating means, means carried by said rolling bodies for tripping said controlling means and setting the elevating means into operation, and means actuated independently of said rolling bodies for stopping said elevating means within a predetermined interval of time sufficient to trans-

port a rolling body from the lower to a higher level.

2. A toy roller coaster, having in combination, a continuous track on which a plurality of rolling bodies are supported, said track having a portion thereof positioned at a higher level than the remaining portions of the track to permit the rolling bodies to move by gravitational force from the higher to the lower level of said track, elevating means for carrying the rolling bodies from the lower to the higher level, means for controlling the operation of said elevating means, means associated with said rolling bodies for tripping the controlling means to set the elevating means into operation, and means for stopping said elevating means within a predetermined interval of time sufficient to transport a rolling body from the lower to a higher level, means for stopping one of said rolling bodies at a predetermined point, and means actuated by another of said rolling bodies for restarting the rolling body that had come to rest.

3. A toy roller coaster, having in combination, a continuous track on which a plurality of rolling bodies are supported, said track having a portion thereof positioned at a higher level than the remaining portions of said track to permit the rolling bodies to move by gravitational force from the higher to the lower level of said track, elevating means for carrying the rolling bodies from the lower to the higher level, and means for momentarily stopping said rolling bodies at a predetermined point during their travel from the higher level to the lower level.

4. A toy roller coaster, having in combination, a continuous track on which a plurality of rolling bodies are supported, said track having a portion thereof positioned at a higher level than the remaining portions of the track to permit the rolling bodies to move by gravitational force from the higher to the lower level of said track, elevating means for carrying the rolling bodies from the lower to the higher level, means for momentarily stopping said rolling bodies at a predetermined point during their travel from the higher level to the lower level, and means for restarting said rolling bodies on their way which is set into operation when another of said rolling bodies reaches a predetermined point on said continuous track.

5. A toy roller coaster, having in combination, a continuous track on which a plurality of rolling bodies are supported, said track having a portion thereof positioned at a higher level than the remaining portions of said track to permit the rolling bodies to move by gravitational force from the higher to the lower level of said track, elevating means for carrying the rolling bodies from the lower to the higher level, means for momentarily stopping the rolling bodies at a predetermined point during their travel from

the higher to the lower level; a trip located at a predetermined point on said track and adapted to be actuated by engagement with a rolling body on said track, and means for restarting said rolling body that is momentarily stopped and which means is set into operation by said trip.

6. A toy roller coaster, having in combination, a continuous track on which a plurality of rolling bodies are supported, a plurality of spaced driving mechanisms associated therewith for imparting movement to said rolling bodies, means permitting the rolling bodies to roll by gravity from one driving mechanism to the other, and means controlling the operation of said driving mechanisms to operate the same for a predetermined length of time.

7. A toy roller coaster, having in combination, a continuous track on which a plurality of rolling bodies are supported, a plurality of spaced driving mechanisms associated therewith for imparting movement to said rolling bodies, means for conveying said rolling bodies from one driving mechanism to the other, and means controlling the operation of said driving mechanisms to operate the same for a predetermined length of time.

8. A toy roller coaster, having in combination, a continuous track on which a plurality of rolling bodies are supported, a plurality of spaced driving mechanisms associated therewith for imparting movement to said rolling bodies, means for conveying said rolling bodies from one driving mechanism to the other, and means associated with each driving mechanism for controlling the operation of said driving mechanism to operate the same for a predetermined length of time and which means is set into operation by a rolling body at some remote point on said track.

9. A toy roller coaster, having in combination, a continuous track on which a plurality of rolling bodies are supported, a plurality of spaced driving mechanisms associated therewith for imparting movement to said rolling bodies, means for conveying said rolling bodies from one driving mechanism to the other, and means for automatically starting and stopping said driving mechanisms at predetermined times.

10. A toy roller coaster, having in combination, a continuous track on which a plurality of rolling bodies are supported, a plurality of spaced driving mechanisms associated therewith for imparting movement to said rolling bodies, controlling means actuated by engagement of a rolling body therewith for starting said driving mechanisms at predetermined times, and means for automatically stopping said driving mechanisms at the expiration of a predetermined interval of time.

11. A toy roller coaster, having in combination, a continuous track on which a plurality of rolling bodies are supported, a plurality of spaced driving mechanisms associated therewith for imparting movement to said rolling bodies, controlling means comprising trips arranged to be depressed by engagement of a rolling body therewith for starting said driving mechanisms at predetermined times, and means for automatically stopping said driving mechanisms at the expiration of a predetermined interval of time.

In testimony whereof I have affixed my signature.

GEORGE WM. KEILHOLZ.
